UNITED STATES PATENT OFFICE.

EMIL M. KRAMER, OF PAXTON, ILLINOIS.

INTERNAL-COMBUSTION ENGINE.

1,134,684.

Specification of Letters Patent.

Patented Apr. 6, 1915.

Application filed May 6, 1912. Serial No. 695,364.

To all whom it may concern:

Be it known that I, EMIL M. KRAMER, a citizen of the United States, residing at Paxton, in the county of Ford and State of Illinois, have invented a new and useful Improvement in Internal-Combustion Engines, of which the following is a specification.

My primary objects, generally stated, are to provide novel improvements in the valve mechanism of internal combustion engines for compressing the charges before admission to the engine cylinders; to provide novel means for starting the engine without manual cranking thereof, said means being preferably so constructed that they will operate while the engine is running to compress charges to be fired, and may be manually operated, when the engine is at rest, to compress charges for introduction into the engine cylinders for firing therein to start the engine; to provide for the driving of the engine in either the forward or reverse directions; to provide means whereby the engine may be operated to deliver an impulse upon each forward stroke, or upon alternate forward strokes, of the piston; to utilize to the maximum extent the suction produced in the engine in its operation, for drawing the vaporized fuel into the latter; to provide for the preheating of the vaporized fuel before it enters the engine in order that the greatest efficiency may be obtained therefrom; and generally to provide improvements in engines of this type to the end of causing them to perform their functions to better advantage and to secure the maximum of power commensurate with the fuel consumption.

Referring to the accompanying drawings in which I have illustrated certain of the many forms in which my invention may be embodied, Figure 1 is a view in vertical sectional elevation (taken at the irregular line 1 on Fig. 6 and viewed in the direction of the arrow) of an engine which may be operated to deliver an impulse upon each forward stroke, or upon alternate forward strokes, of the piston, constructed in accordance with my invention, this view showing the relative positions of parts when the charge in the cylinder illustrated is about to be fired, the parts of the construction shown being illustrated in the positions assumed by them while the engine is operating under its self-contained power. Fig. 2 is a view simi-

lar to Fig. 1 showing the charge-compressing and valve-mechanism in its lowermost position under manual operation for compressing a charge for introduction into the cylinder co-operating therewith for starting the engine. Fig. 3 is a broken section taken at the line 3 on Figs. 1 and 4 and viewed in the direction of the arrows. Fig. 4 is a section taken at the line 4 on Fig. 3 and viewed in the direction of the arrow. Fig. 5 is a section taken at the line 5 on Fig. 3 and viewed in the direction of the arrow. Fig. 6 is a broken section taken at the line 6 on Fig. 1 and viewed in the direction of the arrow, this view showing one of the plurality of the cylinders of the engine and the mechanism co-operating therewith. Fig. 7 is a view similar to Fig. 6 with certain of the parts omitted, the better to disclose certain details of the valve-sleeve-operating mechanism. Fig. 8 is a section taken at the line 8 on Fig. 6 and viewed in the direction of the arrow, this view showing details of the valve-sleeve-operating mechanism in the position they normally occupy while the engine is running: Fig. 9 is a view like Fig. 8, showing the parts of the mechanism illustrated in Fig. 8 in the position they occupy when manually operated for controlling the introduction of the charge into the engine to start the latter. Fig. 10 is a section taken at the line 10 on Fig. 6 and viewed in the direction of the arrow. Fig. 11 is a section taken at the line 11 on Fig. 9 and viewed in the direction of the arrow. Fig. 12 is a broken section taken at the irregular line 12 on Fig. 1 and viewed in the direction of the arrow. Fig. 13 is a view similar to Fig. 1 of another embodiment of my invention. Fig. 14 is a view similar to Fig. 1, showing another modification of the charge-compressing and valve-mechanism. Fig. 15 is an enlarged sectional view taken at the line 15 on Fig. 1 and viewed in the direction of the arrow. Fig. 16 is a broken view in elevation of the carburetor for the engine, and the manifold-connections between the carburetor and the engine. Fig. 17 is a sectional view of one of the similar valve-equipped branch pipes of the manifold shown in Fig. 16. Figs. 18 and 19 are broken views in sectional elevation of the upper ends of engines constituting other embodiments of my invention; and Fig. 20, a broken view of the charge-compressing and valve mecha-

nism of the engine illustrated in Fig. 19, this view showing the valve and compression mechanism in its lowermost position.

Referring particularly to Figs. 1 to 12, inclusive, the cylinders of the engine are illustrated at 25 and surmount a crank-case 26 into which they open at their lower ends and to which they are secured as by screws 27. The cylinders 25, which are preferably water-jacketed as indicated at 28 and are provided with the usual jump-spark plugs 29 at their upper ends, contain pistons 30 adapted to be reciprocated in said cylinders and in their lowermost position open the interiors of said cylinders to exhaust-ports 31 therein. The pistons 30 are connected, through the medium of piston-rods 32, with cranks 33 carried by a crank-shaft 34 extending through the crank-case 26 and journaled in bearings 35 therein, all in accordance with the well known practice of constructing engines.

Surmounting the crank-case 26 and secured thereto, as by screws 36, are valve cylinders 37, one of said cylinders being provided for each cylinder 25 and arranged preferably at one side of the latter, as represented. A port 38 leads from the interior of each cylinder 37 at the upper end of the latter into the respective cylinder 25, with which it co-operates, and a port 39 leads from each cylinder 37, a slight distance below the port 38, into a conduit 40 provided in the wall of the respective cylinder with which it co-operates and extending spirally about the latter, as represented in Figs. 1 and 15, the conduits 40 being in communication with the several branches 41 of a manifold 42 opening into the carburetor 43 which may be of any suitable construction. By this arrangement, it is designed that the vaporized fuel sucked from the carburetor 43 into the manifold 42 by the action of the engine will be caused to pass around the cylinders 25, where it will be subjected to the heat of the latter, and thence pass into the cylinders 37 for compression therein and final discharge into the cylinders 25 as hereinafter fully explained, thus causing the vaporized fuel to be heated preliminary to its discharge into the engine-cylinders, with the manifest advantages.

Each cylinder 37 contains a reciprocable valve-sleeve 44, the upper end of each of which is of enlarged diameter, as represented at 45, and operates in the correspondingly enlarged portion 46 of the cylinder-bore 47, each sleeve 44, which contains a piston 48 slidable therein as hereinafter described, being provided with a passage 49 which is adapted to be moved into and out of registration with the respective ports 38 and 39 by reciprocating the sleeve as hereinafter described.

In the operation of the engine the sleeves

44 and pistons 48 are caused to be reciprocated in the cylinders 37 independently of each other for the purpose of drawing charges into the cylinders 37, compressing them therein and thereafter discharging the compressed charges into the engine cylinders for firing therein, a description of the means illustrated for this purpose being as follows: Extending through the crank-case 26 and journaled in bearings 50 therein is a shaft 51 provided with cranks 52 corresponding in number to the cranks 33, and so arranged on the shaft 51 as to cause them to occupy the same relative positions as those occupied by the cranks 33, as illustrated in those shown in Fig. 1. The cranks 52 are pivotally connected with connecting-rods 53 at the lower ends of the latter, the upper ends of the rods 53 being journaled on studs 54 carried by heads 55 provided on the lower ends of piston rods 56 connected with the pistons 48, the heads 55 being journaled on studs 56 secured to blocks 57 slidably confined in guides 58 on rock-members 59 journaled on studs 60, secured in bosses 61 in the crank-case 26, the boss 61 for one of the end-cylinders being formed as a part of an end-wall 62 of the case 26, whereas the other bosses 61 are provided on the inner ends of brackets 63 carried on the interior of said crank-case. Secured on the shaft 51 adjacent to the respective cranks 52 are eccentrics 64 surrounded by straps 65 provided with lugs 66 pivotally connected, as indicated at 67, with the lower ends of links 68, the latter being pivotally connected, as indicated at 69, with the lower ends of the respective sleeves 44. The lugs 66 are pivotally connected as indicated at 67 with links 70 which are pivotally connected as indicated at 71 with the respective rock-members 59 eccentrically of the pivots 60, as indicated in Figs. 8 and 9, for a purpose herein-after explained.

The rock-members 59 are equipped with segmental gears 72 meshing with segmental gears 73 provided on a shaft 74 journaled in bearings 75 in the ends of the crank-case 26 and provided with an operating handle 76 through the medium of which the segmental gears 72 and the parts connected therewith may be oscillated for the purpose herein-after explained.

In the construction now being described, the shaft 51 is adapted to be rotated by the shaft 34 through the medium of gear-connections, the said connections illustrated being of a character adapting the shaft 51 to be rotated either at a one to one ratio or one to two ratio, relative to the shaft 34, as desired. A description of these means being as follows: The shaft 51 has fixed to it two gears 76 and 77 of different diameters and spaced apart as represented in Fig. 8, these gears meshing with gears 78 and 79 jour-

naled on the shaft 34, the gears 76 and 78 being of the same size and the gear 79 being one-half the size of the gear 77. Splined on the shaft 34, as indicated at 80, is a clutch-sleeve 81 adapted to be moved longitudinally of the shaft 34 but revoluble therewith. The sleeve 81 is provided with a groove 82 into which the forked end 83 of a shifting-lever 84 fulcrumed as indicated at 85 on a lug 86 on the engine base, extends. The sleeve 81 is provided with laterally projecting pins 87 and 88 which extend in opposite directions and are adapted to be alternately projected into openings 89 and 90 respectively in the gears 78 and 79. It will be understood that by this arrangement either of the gears 78 or 79 may be clutched to the shaft 34 for driving the shaft 51 at the same speed or one-half the speed of the shaft 34, as desired. In the arrangement illustrated, the spark-timing device usually employed in internal combustion engines is represented at 91, the rotary element of which is journaled in an extension 92 of the engine-frame and is equipped with a gear 93 meshing with a similar gear 94 fixed on the shaft 51, these gears being of the same size in order that the timer shall operate at the same speed as the shaft 51.

30 The normal operating position of the mechanism for actuating the sleeves 44 and pistons 48 is that illustrated in Figs. 1, 6, 7, 8, 10, 11 and 12. Assuming that the clutch 81 is in engagement with the gear 78 for driving the shaft 51 at the same rate of speed as the shaft 34, and that the engine is operating under its own power, downward movement of the pistons 30 in the respective cylinders 25 under the action of exploded charges therein operates to turn the shafts 34 and 51 in the direction of the arrows in Fig. 1, with the result of causing the respective sleeves 44 and pistons 48 to be drawn downwardly, in succession, in their cylinders 37 by reason of their eccentric connections with the shaft 51, as hereinbefore described. The initial downward movement of the sleeve 44 operates to move its passage 49 out of engagement with the co-operating conduit 38, and before the piston 48 has reached the limit of its downward movement said conduit has been moved into registration with the inlet conduit 40. The effect of drawing the piston 48 downwardly in its surrounding sleeve 44 is to create a suction in the upper end of the sleeve which is not relieved until the conduit 49 in the latter is brought into registration with the conduit 40 whereupon gas is sucked from the carburetor 43 into the sleeve 44 above the piston 48 therein. In the ascending movement of the pistons 30 the sleeves 44 and pistons 48 are caused to rise in the respective cylinders 37, the sleeves 44 rising to bring their ports 49 into registration with the re-

5 10 15 20 25 30 35 40 45 50 55 60 65 70 75 80 85 90 95 100 105 110 115 120 125 130

spective ports 38. The pistons 48 rise in the sleeves 44 against the confined volumes of vaporized fuel which was sucked into the sleeves 44, as hereinbefore described, and serve to compress the same. As soon as the sleeves 44 have risen sufficiently far to bring their conduits 49 into registration with the ports 38, the charges thus compressed in the sleeves 44 are caused to discharge into the respective cylinders 25 above the pistons 30 therein, the arrangement of the operating mechanism for the pistons 48 being so constructed and arranged that when the pistons 30 are on their firing strokes, as illustrated of the one disclosed in Fig. 1, its co-operating piston 48 will close the conduit 49 to the interior of the sleeve 44 in which it operates. It will be understood from the foregoing that as the pistons 30 near the limits of their downward movements they will uncover the exhaust-ports 31 and thus permit the spent gases to escape from the cylinders 25, and that during said exhaust the interior of the sleeves 44 are closed to the interior of the cylinders 25, so that there is no chance for any fuel discharging from the conduits 40 into the conduits 38. It will also be understood from the foregoing that the pistons 48 serve, in succession, to alternately suck charges into the respective sleeves 44 and compress the same therein and discharge them into the respective cylinders 25 wherein the charges are fired through the medium of the spark-plugs 29 when the pistons 30 are on their firing strokes.

When the engine is at rest it may be started in the following manner: The operator swings the operating handle 76 to the left in Fig. 1, thereby turning the shaft 74 and the gears 73 thereon to the left in said figure. As the gears 73 are in mesh with the gears 72, thus operating the handle 76 causes the gears 72 to turn to the right in Fig. 1 and thereby rock the members 59 to the position illustrated in Figs. 2 and 9. Thus 110 operating the members 59 causes the piston 48 and sleeve 44 which co-operate with the piston 30 which when the engine is at rest, is in the uppermost position, to be moved downwardly a distance equal or substantially equal to that which they are moved in the normal operation of the engine, as hereinbefore described, thereby moving said sleeve 44 into registration at its port 49 with the conduit 40 and sucking a charge into the sleeve. The operator then throws the handle 76 in the opposite direction which causes the parts to assume the position illustrated in Fig. 1, thereby returning the sleeve 44 and piston 48 to their normal position, and in so doing, causing the piston 48 to compress the charge of vaporized fuel sucked into the sleeve 44 and upon the movement of the conduit 49 into registration with the conduit 38, forcing the compressed charge 130

into the cylinder 28 coöperating therewith wherein the charge is fired through the medium of the spark-plug 49 and the engine commences to operate. It will be understood that the manual operation just described serves to operate the sleeve 44 and piston 48 to produce the same result as that effected in the normal operation of the mechanism under the power of the engine 10 while running.

As the distance traveled by the pistons 48 in the manual operation described depends upon the distance between the pins 56^a and the pivots 60 for the members 59, it will be understood that the piston 48 which is connected with one of the cranks 52 which occupies the highest position will be given the greatest movement in its coöperating sleeve 44 when the lever 76 is operated, and that the distances which the other pistons 48 will be moved will be correspondingly reduced, depending on the positions their coöperating cranks 52 occupy, the lower the crank 52 the less movement its coöperating piston 25 will have, when the lever 76 is operated as described. Thus when the lever 76 is swung to the left in Fig. 1, the greatest throw will be imparted to the piston 48 which coöperates with one of the pistons 30 which occupies the highest position when the engine 30 is at rest, whereby the effective charge introduced into the engine discharges into the cylinder the piston in which is on its firing stroke.

The parts of the construction are so arranged that when a piston 30 is in a position in which its coöperating exhaust 31 is open the pivotal connection 56^a between the members 53 and 56 which drive the piston 48 coöperating with said piston 30 extends into substantial alinement with the pivot 60 and thus substantially no movement is imparted to said piston 48, when the lever 76 is actuated as hereinbefore stated, which prevents discharge of charges into the engine-cylinders when the exhausts therein are open.

It will be noted that the mechanism for operating the sleeves 44 and pistons 48 is so constructed that the same movement will be given the pistons 48 and sleeves 44, whether the shaft 51 is turning in one direction or the other and thus the engine may be operated in either direction in starting it as described, or reversed while operating, by retarding or advancing the spark as the case may be as will be manifest to those skilled in the art.

The above description of the operation of the machine relates to the latter when it is being operated to deliver impulses upon each forward stroke of the piston. If it is desired to operate the engine so as to deliver an impulse upon each alternate for-

ward stroke of the piston, the operator 65 shifts the sleeve 81 toward the gear 79 (Fig. 5) to cause the pin 87 to extend into the recess 89, thereby clutching said gear to the shaft 34 and causing the shaft 51 to rotate at one-half the speed of the shaft 34. Under such conditions the pistons 30 will make two complete reciprocations with each complete reciprocation of the piston 48, otherwise the operation of the engine will be the same as that described of the engine 75 when operating to deliver an impulse upon each forward stroke of the piston, excepting that the pistons 30 will produce idle compressions every other upward stroke and in alternation with the upward strokes of the 80 pistons 48.

Referring to the construction illustrated in Fig. 13, the engine therein shown operates upon the same principle as the engine of the preceding figures. In this arrangement, the engine is adapted to be operated to deliver an impulse each forward stroke of the piston only and the sleeves 44 and pistons 48 instead of being operated from a supplemental shaft driven from the engine shaft 34 are 90 operated directly therefrom and consequently at a one to one ratio relative to the engine pistons, the following being a description of the mechanism for driving the sleeves 44 and pistons 48. Secured to the 95 shaft 34 adjacent to each of the cranks 33 are eccentrics 95 and cams 96, the cams 96 being provided with continuous cam-slots 97 into which rollers 98 carried on the free ends of links 99, pivoted as indicated at 100, 100 to lugs 101 on the crank-case of the engine, extend. The eccentrics 95 are surrounded by eccentric straps 102 provided with upwardly extending arms 103 terminating at their upper ends in heads 104 pivoted as 105 indicated at 105 to the sliding members 57 guidedly confined on the rocking-members 59. The connecting-rods for the pistons 48 in this construction are illustrated at 106 and are pivotally connected, as indicated at 110 107, with the respective heads 104 on the arms 103. The sleeves 44 are pivotally connected, as indicated at 108, with the upper ends of links 109 which are formed with break-joints 110 and are pivotally connected 115 at their lower ends as indicated at 111, with the respective links 99 intermediate the rollers 98 and the pivotal connections of said links with the crank-case at 100. The links 109 are connected at their break-joints 110 120 with the respective rock-members 59 through the medium of links 112, the pivotal connections of the latter with the members 59 being located above the points at which the members 59 are pivotally supported.

The normal position of the members 59 is that illustrated of the one shown in Fig. 13, the piston of the engine cylinder shown

in Fig. 13 being on its firing stroke. As the piston 30 is driven downward in the operation of the engine under the explosion of a charge in the cylinder 25, it turns the shaft 5 34 in the direction of the arrow in Fig. 13, with the result of rotating the cams 96 and eccentrics 95 thereon. As the piston 30 descends, its coöperating piston 48 and sleeve 44 are drawn downward, the sleeve 44 being 10 given a comparatively rapid initial downward movement by reason of the pin 98 engaging with an abrupt portion 113 of the cam 96. The piston 48 is drawn down by the rotation of the eccentric 95 which serves 15 to pull the block 57 downwardly in the rock-member 59, the piston 48 in this action serving to suck into the sleeve 44 above said piston a charge of vaporized fuel from the carbureter through the conduit 40. The 20 parts are so timed that as the piston 30, after uncovering the exhaust 31 for discharging the burnt gases, rises in its cylinder 25, the roller 98 will be engaged by the opposed abrupt portion 114 of the cam 96 to move 25 the sleeve 44 upwardly to cause its conduit 49 to register with the conduit 38, and to cause the eccentric 95 to force the block 57 upwardly in the rock-member 59 to raise the piston 48 in the sleeve 44, thereby compressing 30 in the sleeve 44 the charge of vaporized fuel sucked into the latter in its downward movement, as hereinbefore explained, and discharging the compressed charge into the coöperating cylinder 25, wherein it is fired 35 for driving the piston 30 therein downwardly.

The engine illustrated in Fig. 13 is operated for starting it in the same manner as explained of the construction shown in the preceding figures. Thus, to start the engine the operator swings the operating lever 76 upwardly to the left in Fig. 13 for rocking all of the rock-members 59 to the right in Fig. 13 to the position indicated by the dotted lines 119. The piston 48 and sleeve 44 which coöperate with one of the pistons 30 which when the engine is at rest is on the firing stroke, will thus be drawn downwardly in the cylinder 37 containing them 45 and given the same movement as is produced when the engine is operating under its own power, as hereinbefore explained, for sucking a charge into the sleeve 44, compressing it therein and discharging it into the cylinder 25 coöperating with the sleeve 44 and piston 48 thus operated, and above the piston 30 therein, wherein the compressed charge is ignited by the spark-plug 29 for driving the piston 30 downwardly to 50 start the engine.

In order that the movements of the sleeves 44 and pistons 48 and the operating mechanism therefore be clearly understood, I have represented by dotted lines in Fig. 13 some

of the positions which will be occupied by 65 said parts. In the downward movement of the piston 30 the links 99, 109 and 112, will be drawn to the positions indicated by the dotted lines 115, 116 and 117, respectively, and when the operating handle 76 is moved 70 upwardly to the left in Fig. 13, for manually producing a compression in the sleeve 44, as hereinbefore explained, assuming the piston 30 to be in the position illustrated in said figure, the link 109, rock-member 59 75 and connecting rod 106, will occupy the positions represented by the dotted lines 118, 119 and 120, respectively.

The construction illustrated in Fig. 14 is the same as that shown in Fig. 1, excepting 80 that the sleeve 44 instead of being operated by a mechanical connection between it and the shaft 51, is designed to be operated by frictional engagement of the piston 48 therewith. In this arrangement the cylinder 37 85 is shouldered as represented at 120 to form a stop coöperating with the shoulder portion 121 of the enlarged portion 45 of the sleeve 44 for limiting the downward movement of the sleeve in said cylinder, and provision is made for producing the greater friction between the piston 48 and the sleeve 44 than exists between the sleeve 44 and the cylinder 37, as by providing a tighter 90 rotating joint between the piston 48 and sleeve 44 than is provided between said piston and cylinder 37. Thus the piston 48 in its initial downward movement carries with it the sleeve 44 to open the port 49 to the conduit 40, the piston 48 in its continued 95 downward movement sucking a charge into the sleeve 44. As the piston 48 begins its continued upward movement it carries the sleeve 44 with it until the latter abuts against the upper end of the cylinder 37, in which position the port 39 is closed to the sleeve and the port 49 is brought into registration of the port 38. The piston 48 in its continued 100 upward movement in operating upon the charge of vaporized fuel drawn into the sleeve 44 produces compression thereof and forces it into the cylinder 25 for firing, it being understood that the operation of the piston 48 and sleeve 44 in this construction 105 is the same whether the piston be operated by the rotation of the shaft 34 or by operating the lever 76.

In the construction illustrated in Fig. 18, the feature of providing a sleeve for coöperation with the charge-compressing piston is 110 omitted, and in its place the passages between the cylinders 37 and the cylinders 25 and the carbureter are provided with check-valves operating to permit charges to be sucked into the cylinders 37 when the pistons 48 therein move downwardly and be forced from said cylinders into the main cylinders of the engine as the pistons 48 115 120 125

rise in the cylinders 37. Thus, each conduit represented at 122 and corresponding with the conduits 38 is provided with a check-valve 123 which co-operates with a seat 124 and opens toward the cylinder 25, and the conduits represented at 125 and from which pipes 126 lead into the respective conduits 40, contain check-valves 126^a which co-operate with seats 126^b and open toward the cylinders 37. The pistons 48 of this construction may be operated in any desirable manner as by the mechanism hereinbefore described, to cause their reciprocations in the cylinders 37 to be so timed with relation to the pistons 30 as to cause them to suck into the cylinders 37 the charges of volatilized fuel from the carburetor and compress said charges in the last referred to cylinders and force them into the cylinders 25 while the pistons 30 are rising therein.

It will be understood that when the pistons 48 are connected up with any of the piston-actuating mechanisms hereinbefore described, they will be caused to perform the functions stated either while the engine is operating normally under its own power or when manually actuated as explained, while the engine is at rest, for compressing charges and discharging them into the cylinder the piston of which is on the firing stroke.

In the constructions illustrated in Figs. 19 and 20, I have illustrated still another embodiment of my invention. In this case the cylinder in which the charges are compressed is represented at 127 and corresponds with the cylinder 37 of the preceding figures. The main cylinder 25 is connected at its upper end with the interior of the cylinder 127 through the medium of a passage 128 which contains a check-valve 129 similar to the check-valve 123. The port 40 of the cylinder 25 communicates with a conduit 130 which extends peripherally about the inner surface of the cylinder 127 and leads upwardly in the latter and opens through the wall of said cylinder at a point diametrically opposite to the conduit 128. The conduit 130 is formed with a valve-seat 131 with which a check-valve 132 co-operates, and communicates with a by-pass 133 which opens into the interior of the cylinder 127 at the upper end of the latter. The piston for compressing the charges is represented at 134, said piston containing a socket 135 in which the depending head 136 carried on the top 137 of the cylinder 127, extends. The piston 134 is provided with a transversely extending passage 138 which opens into the socket 135 and into a peripheral groove 139 in the piston 134. The parts just described are so constructed that when the piston 134 is at the limit of its upward stroke, the head 136 will extend into the socket 135 to a point below the passage 138 and the peripheral groove 139 will be in reg-

istration with the conduit 128 and the upper end of the conduit 130.

It is designed that the piston mechanism of the construction illustrated in Fig. 19 be timed in its operation relative to the piston 30 as described of the preceding constructions, and to this end it may be driven through the medium of the hereinbefore described piston-driving mechanism or any other suitable mechanism, to cause it to compress the charges and discharge the same into the main cylinder of the engine for driving the piston therein.

Assuming that the parts of the engine are in the positions illustrated in Fig. 19 in which the piston 30 is on its firing stroke, downward movement of the piston 134 will tend to produce suction action in the cylinder 127 above the piston 134 and in the chamber 135. The suction action above the piston 134 as the piston descends serves to suck into it a charge from the carburetor through the conduit 130, past the valve 131, and through the by-pass 133 into the cylinder 127, and as soon as the groove 139 registers with the lower end of the conduit 130, as represented in Fig. 20, the chamber 135 by reason of the comparative vacuum therein will be filled with volatilized fuel from said conduit. In the upward movement of the piston 134 the charges sucked into the cylinder 127 above said piston and into the chamber 135 are compressed therein, and as soon as the piston 134 has been raised to a position in which its groove 139 registers with the conduit 128 and the upper end of the conduit 130, the charge compressed in the cylinder 127 above the piston 134 and that portion which was compressed in the chamber 135 will discharge from the cylinder 127 and into the conduit 128 from whence it passes into the cylinder 25 above the piston 30 therein for firing. It will be noted that the piston 134 will operate to perform the functions just described when it is being operated either by the engine operating under its own power or when manually actuated to pump a compressed charge, for firing, into the cylinder containing the piston which is on the firing stroke. Each of the branch pipes 41 contains a check-valve 140 which closes toward the carburetor 43, and thus when suction is produced in any of the cylinders 37 of the engine the suction action thus produced is concentrated on the carburetor which is of advantage in structures of this character as it insures the utilization to the maximum extent of the power of the suction action of the engine, in operating, on the fuel supply.

While I have illustrated and described certain specific constructions of engines constituting embodiments of my invention I do not wish to be understood as intending to limit it to such constructions, as the same

may be variously altered and modified without departing from the spirit of my invention.

What I claim as new and desire to secure by Letters Patent is:

1. In an internal combustion engine having a drive-shaft, the combination with its working-cylinder and the piston therein, of charge-compressing means coöperating with said cylinder for intermittently supplying thereto compressed charges of fuel, means for operating said charge-compressing means from the drive shaft of the engine including members pivotally connected together, and shiftable guiding means therefor, and means for shifting said guiding means, when said piston is at rest, for operating said charge-compressing means, for the purpose set forth. 15
2. In an internal combustion engine having a drive-shaft, the combination with its working-cylinder and the piston therein, of charge-compressing means coöperating with said cylinder for intermittently supplying thereto compressed charges of fuel, means for operating said charge-compressing means from the drive shaft of the engine including members pivotally connected together, a shiftable guide member, a block 20 operatively connected with said pivotally connected members and movable on said guide member, and means for shifting said guide member when said piston is at rest for operating said charge-compressing means, for the purpose set forth. 25
3. In an internal combustion engine having a drive-shaft, the combination with its working-cylinder and the piston therein, of charge-compressing means coöperating with said cylinder for intermittently supplying thereto compressed charges of fuel, means for operating said charge-compressing means from the drive shaft of the engine including members pivotally connected together and pivotally supported guiding means therefor, and means for oscillating said guiding means when said piston is at rest, for operating said charge-compressing means, for the purpose set forth. 30
4. In an internal combustion engine having a drive-shaft, the combination with its working-cylinder and the piston therein, of charge-compressing means coöperating with said cylinder for intermittently supplying thereto compressed charges of fuel, means for operating said charge-compressing means from the drive shaft of the engine including members pivotally connected together, a pivoted guide member, and a block 35 operatively connected with said pivotally connected members and movable on said guide member, and means for oscillating said guide member when said piston is at rest for operating said charge-compressing means, for the purpose set forth. 40
5. In an internal combustion engine, having a drive-shaft, the combination with its working-cylinder and the piston therein, of charge-compressing means coöperating with said cylinder for intermittently supplying thereto compressed charges of fuel, means for operating said charge-compressing means from the drive shaft of the engine, including a crank, members pivotally connected together and operatively connected, 45 respectively, with said crank and with said charge-compressing means, and shiftable guiding means therefor, and means for shifting said guiding means, when said piston is at rest, for operating said charge-compressing means, for the purpose set forth. 50
6. In an internal combustion engine, the combination with its working-cylinder and the piston therein, of charge-compressing means coöperating with said cylinder for intermittently supplying thereto compressed charges of fuel including an auxiliary cylinder, and a sliding sleeve and a charge-compressing piston therein, said auxiliary cylinder containing ports communicating with said working-cylinder and adapted to communicate with a source of fuel supply, respectively, and said sleeve containing a port adapted to alternately register with said auxiliary-cylinder ports, means, operable when said first-named piston is at rest, for operating said charge-compressing means to discharge a compressed charge of fuel into said working-cylinder above the piston 55 therein for starting the engine, and means operated by said first named piston in its movements for actuating said charge-compressing means, for the purpose set forth. 60
7. In an internal combustion engine, the combination with its working-cylinder and the piston therein, of charge-compressing means coöperating with said cylinder for intermittently supplying thereto compressed charges of fuel including an auxiliary cylinder, and a sliding sleeve and a charge-compressing piston therein, said auxiliary cylinder containing ports communicating with said working-cylinder and adapted to communicate with a source of fuel supply, respectively, and said sleeve containing a port adapted to alternately register with said auxiliary-cylinder ports, means operatively connected with said sleeve and with said last named piston and operable, when said first-named piston is at rest, for reciprocating said charge-compressing piston and said sleeve to discharge a compressed charge into said working cylinder above the piston 65 therein, and means operated by said first named piston in its movements for reciprocating said charge-compressing piston and said sleeve, for the purpose set forth. 70
8. In an internal combustion engine, the combination with its working-cylinder and 75

- the piston therein, of charge-compressing means coöperating with said cylinder for intermittently supplying thereto compressed charges of fuel including an auxiliary cylinder, and a sliding sleeve and a charge-compressing piston therein, said auxiliary cylinder containing ports communicating with said working-cylinder and adapted to communicate with a source of fuel supply, respectively, and said sleeve containing a port adapted to alternately register with said auxiliary-cylinder ports, and means for operating said sleeve and charge-compressing piston including members pivotally connected together and driven from said drive shaft and operatively connected with said sleeve and charge-compressing piston, and means operatively connected with said pivotally connected members for actuating said sleeve and charge-compressing piston when said first named piston is at rest for the purpose set forth.
9. In an internal combustion engine, the combination with its working-cylinder and the piston therein, of charge-compressing means coöperating with said cylinder for intermittently supplying thereto compressed charges of fuel including an auxiliary cylinder, and a sliding sleeve and a charge-compressing piston therein, said auxiliary cylinder containing ports communicating with said working-cylinder and adapted to communicate with a source of fuel supply, respectively, and said sleeve containing a port adapted to alternately register with said auxiliary-cylinder ports, means for operating said sleeve and charge-compressing piston including pairs of members pivotally connected together, a member of each pair thereof being connected with said charge-compressing piston and with said sleeve, means for reciprocating said pivotally connected members, a pivotally supported guide member operatively engaging with the said pair of members connected with said charge-compressing piston for guiding the movements thereof and means connected with the other pair of said members and with said guide member eccentrically of the axis about which the latter turns when oscillated, and means operatively connected with said pivotally supported guide member for oscillating the latter, for the purpose set forth.
10. In an internal combustion engine, the combination with its working-cylinder and the piston therein, of charge-compressing means coöperating with said cylinder for intermittently supplying thereto compressed charges of fuel including an auxiliary cylinder, and a sliding sleeve and a charge-compressing piston therein, said auxiliary cylinder containing ports communicating with said working-cylinder and adapted to communicate with a source of fuel supply, respectively, and said sleeve containing a port adapted to alternately register with said auxiliary-cylinder ports, and means for operating said sleeve and charge-compressing piston including members pivotally connected together and driven from said drive shaft and operatively connected with said sleeve and charge-compressing piston, means for guiding the movements of said pivotally connected members, and means for shifting said guiding means for actuating said sleeve and charge-compressing piston when said first named piston is at rest, for the purpose set forth.
11. In an internal combustion engine, the combination with its working-cylinder and the piston therein, of charge-compressing means coöperating with said cylinder for intermittently supplying thereto compressed charges of fuel including an auxiliary cylinder, and a sliding sleeve and a charge-compressing piston therein, said auxiliary cylinder containing ports communicating with said working-cylinder and adapted to communicate with a source of fuel-supply, respectively, and said sleeve containing a port adapted to alternately register with said auxiliary-cylinder ports, means for operating said sleeve and charge-compressing piston including pairs of members pivotally connected together, a member of each pair thereof being connected with said charge-compressing piston and with said sleeve, means for reciprocating said pivotally connected members, a pivotally supported guide member operatively engaging with the said pair of members connected with said charge-compressing piston for guiding the movements thereof and means connected with the other pair of said members and with said guide member eccentrically of the axis about which the latter turns when oscillated, and means operatively connected with said pivotally supported guide member for oscillating the latter, for the purpose set forth.
12. In an internal combustion engine, the combination with its working-cylinder and the piston therein, of charge-compressing means coöperating with said cylinder for intermittently supplying thereto compressed charges of fuel, means for operating said charge-compressing means from the drive shaft of the engine including members pivotally connected together and pivotally supported guiding means therefor, the parts described being so constructed and arranged that when the piston is at the lowermost position on its stroke the pivotal connection between said pivotally connected members will extend close to the point at which said guiding means are pivotally supported, and means for oscillating said guiding means when said piston is at rest, for operating said charge-compressing means, for the purpose set forth.
13. The combination with the cylinders of an internal combustion engine and pistons therein, of charge-compressing pumps communicating respectively with said cylinders, means for operating said pumps in

timed relation to the respective cylinders with which they coöperate, and means for operating, when the engine is at rest, the one of said pumps which communicates with the cylinder, the parts of which are on the firing stroke when the engine is at rest, for introducing into said cylinder a charge of compressed fuel.

14. The combination with the cylinders of an internal combustion engine and pistons therein, of charge-compressing pumps communicating, respectively, with said cylinders, pivoted guide-members operatively engaged by the reciprocating members of said pumps, and means for actuating the reciprocatory members of said pumps in timed relation to the movement of the pistons in the cylinders with which said pumps respectively coöperate, whereby the reciprocatory member of that pump which coöperates with the cylinder, the piston of which latter is on the firing stroke when the engine is at rest, extends on said guide at a point eccentric to the point of pivotal support of said guide-members, and rocking of the latter causes the reciprocating member of said last referred to pump to be reciprocated to introduce a charge of fuel into said last referred to cylinder.

15. The combination with the cylinders of an internal combustion engine and pistons therein, of charge-compressing pumps communicating, respectively, with said cylinders, pivoted guide-members operatively engaged by the reciprocating members of said pumps, and means operated by the shaft of the engine for actuating the reciprocatory members of said pumps in timed relation to the cylinders with which said pumps respectively coöperate, whereby the reciprocatory member of that pump which coöperates with the cylinder, the piston of which latter is on the firing stroke when the engine is at rest, extends on said guide at a point eccentric to the point of pivotal support of said guide-members, and rocking of the latter causes the reciprocating member of said last referred to pump to be reciprocated to introduce a charge of fuel into said last referred to cylinder.

16. The combination with the cylinder of an internal combustion engine and pistons therein, of charge-compressing pumps communicating, respectively, with said cylinders, pivoted guide-members operatively

engaged by the reciprocating members of said pumps, and means for actuating the reciprocatory members of said pumps in timed relation to the movements of the pistons in the cylinders, with which said pumps respectively coöperate, the axes upon which said pivoted members are movable being substantially in alinement with the connections of said means with said reciprocating parts of the pumps when the pistons are at the ends of their firing strokes, whereby the reciprocatory member of that pump which coöperates with the cylinder, the piston of which latter is on the firing stroke when the engine is at rest, extends on said guide at a point eccentric to the point of pivotal support of said guide-members, and rocking of the latter causes the reciprocating member of said last referred to pump to be reciprocated to introduce a charge of fuel into said last referred to cylinder.

17. The combination of the cylinders of an internal combustion engine and pistons therein, of charge-compressing pumps communicating, respectively, with said cylinders, pivoted guide-members, blocks slideable on said guide-members and to which the reciprocating members of said pumps are connected, rods operatively connected with said blocks in pivotal relation thereto, and means actuated from said engine-shaft for actuating said rods to actuate the reciprocating members of said pumps in timed relation to the movements of the pistons in the cylinders with which said pumps respectively coöperate, the axis upon which said pivoted members are swingable extending in substantial alinement with the pivotal connections of the reciprocating members of said pumps with said blocks when the pistons are at the ends of their firing strokes, whereby the reciprocatory member of that pump which coöperates with the cylinder, the piston of which latter is on the firing stroke when the engine is at rest, extends on said guide at a point eccentric to the point of pivotal support of said guide-members, and rocking of the latter causes the reciprocating member of said last referred to pump to be reciprocated to introduce a charge of fuel into said last referred to cylinder.
